UNITED STATES PATENT OFFICE.

WILLIAM T. LILLY AND ANDREW J. LILLY, OF GLEN MORGAN, WEST VIRGINIA,
ASSIGNORS OF ONE-HALF TO GROVER C. HEDRICK, OF BECKLEY, WEST VIRGINIA.

AUTOMATIC-CLENCH CAR-COUPLING.

1,158,515.

Specification of Letters Patent.

Patented Nov. 2, 1915.

Application filed June 26, 1915. Serial No. 36,561.

To all whom it may concern:

Be it known that we, WILLIAM T. LILLY and ANDREW J. LILLY, citizens of the United States, residing at Glen Morgan, in the county of Raleigh and State of West Virginia, have invented certain new and useful Improvements in Automatic-Clench Car-Couplings, of which the following is a specification, reference being had therein to the accompanying drawing.

This invention relates to new and useful improvements in car couplers, especially adapted for use upon mining cars, etc., and comprises a simple and efficient apparatus of this nature having various details of construction, combinations and arrangements of parts which will be hereinafter fully described, shown in the accompanying drawings and then specifically defined in the appended claims.

Our invention is illustrated in the accompanying drawings, in which:

Figure 1 is a top plan view showing the couplers at the ends of two cars coupled together. Fig. 2 is a central sectional view transversely through the coupler heads, showing the parts about to be coupled. Fig. 3 is a sectional view through the couplers connected together. Fig. 4 is a similar view showing the pin in readiness to be coupled as the couplers come together. Fig. 5 is a detail view of an edge of the coupling pin. Fig. 6 is a bottom plan view, and Fig. 7 is an enlarged detail view of one of the coupler heads.

Reference now being had to the details of the drawings by numeral, 1 designates a chambered projection upon a car 1^x, within which are pivotally mounted upon the pins 11 the coupler members 10, shaped as shown clearly in Fig. 2 of the drawings, and which are provided with angled recesses 12 at their inner ends, said coupler members being mounted in the recesses 14. The wall of said projection is provided with a triangular outlined opening 13 and is chambered as at 15, as shown clearly in Fig. 4 of the drawings, for the reception of the pin 18 which has its upper forward edge convexed as at 18^x and is connected at 26 to the chain 25, which latter is attached to and winds about a crank arm of the rock shaft 21, journaled in the bearings 22 upon the end of the car. Said pin has, at its lower end, a contracted

angled projection 19, beveled as at 20 and is 55 adapted to rest in said position to allow the cars to automatically couple when they come together upon the ledge 17 and, when in a locked position as shown in Fig. 3, said projection 19 extends through the angled 60 opening 13 and rests upon the ledge 30. The chamber in which the pin 18 is mounted has a space 15^x in the upper portion thereof adapted to receive the convexed edge of the pin when elevated to the position shown in 65 Fig. 4.

The coupling head 3 has a shank portion 2 which has an elongated slot 4 therein through which the pin 5 carried by the projection 6 upon the car 6^x passes. A coiled 70 spring is interposed between the pin 5 and the opposite end of the slot and coiled springs 7 are fastened at their inner ends to the pins 8 upon the shank portion 2 and their other ends to the pins 9, as shown 75 clearly in Fig. 2 of the drawings. Said head 3, as shown in Fig. 7, is provided with an emergency link receiving slot 27 and a vertical pin opening 28.

The operation of our invention will be 80 readily understood and is as follows:— When it is desired to couple two cars equipped with our improved coupling apparatus, the gravity pin is supported in the position shown in Fig. 4. When the head 85 3 comes in contact with the forwardly projecting portions of the coupler members 10, as shown in Fig. 2, said coupling members will be tilted upon the pivots 11 and the pin will be pushed back off the ledge 17 90 and, when the edges of the angled recesses 12 come flush with the opposite angled edges of the opening 13, the pin will fall through the latter and the shouldered portion of the pin will rest upon the ledge 30, as shown in 95 Fig. 3 of the drawings, and which will lock the jaws or members 10 in engagement with the laterally projecting portions of the head 3, as shown in Fig. 1. The coiled spring interposed between the pin 5 and the end 100 of the slot 4 will yield to take up shock incident to the couplers coming together, the shank portion 2 being allowed to have a lateral tilting movement through the medium of the springs 7 connected to the rear end. 105 When it is desired to uncouple the car, the operator by turning the rock shaft may cause the pin to be elevated to the position

shown in Fig. 4, thus allowing the coupler members 10 to tilt upon their pivots and allow the head 3 to be released therefrom.

It will be noted from the foregoing that 5 a positive lock is provided which is automatic in its action and so constructed that the pin will be held by gravity in a locked position without any danger of its becoming displaced by accident incident to jars, it 10 being necessary to rock the shaft to which the pin is connected before it may be thrown to such position to allow the couplers to be uncoupled.

What we claim to be new is:—

15 1. A coupler for mining cars, etc., comprising a head which is chambered provided with an angular outlined opening in the bottom thereof, coupler members pivoted within a recess in the chambered portion and having angular outlined recesses in their inner edges, a yielding coupler head adapted for attachment to the end of an adjacent car, a pin having its lower portion contracted and angular in cross section and beveled, pin raising means connected to the latter at one side of its center of gravity, the beveled portion of the pin adapted to contact with the coupling member to separate the same, a yielding coupling member having yielding connections with the end of an adjacent car and adapted to contact with the projections of the coupling members of the cars to be coupled as they come together.

20 2. A coupler for mining cars, etc., comprising a head which is chambered provided with an angular outlined opening in the bottom thereof, coupler members pivoted within a recess in the chambered portion and having angular outlined recesses in their inner edges, a yielding coupler head adapted for attachment to the end of an adjacent car, a gravity coupling pin having an angled extension at its lower end, means connected at one side of the center of gravity of the pin to cause the same to tilt as it is raised, said pin causing the couplers to separate as the pin is raised.

25 3. A coupler for mining cars, etc., comprising a head which is chambered provided with an angular outlined opening in the bottom thereof, coupler members pivoted within a recess in the chambered portion and having angular outlined recesses in their inner edges, a yielding coupler head adapted for attachment to the end of an adjacent car, a gravity coupling pin having an angled extension at its lower end, means connected at one side of the center of gravity of the pin to cause the same to tilt as it is raised, said pin causing the couplers to separate as the pin is raised, the forward edge of the contracted portion of the pin being beveled and adapted to contact with the inner ends of the coupling members as the pin is raised.

40 4. A coupler for mining cars, etc., comprising a head which is chambered and pro-

vided with an angular outlined opening in the bottom thereof, coupler members pivoted within a recess in the chambered portion and having angular outlined recesses in their inner edges, a yielding coupler head adapted for attachment to the end of an adjacent car, a pin having its lower portion contracted and angular in cross section and beveled, pin raising means connected to the latter at one side of its center of gravity, the beveled portion of the pin adapted to contact with the coupling member to separate the same, a yielding coupling member having yielding connections with the end of an adjacent car and adapted to contact with the projections of the coupling members of the cars to be coupled as they come together.

45 5. A coupler for mining cars, etc., comprising a head which is chambered and provided with an angular outlined opening in the bottom thereof, coupler members pivoted within a recess in the chambered portion and having angular outlined recesses in their inner edges, a yielding coupler head adapted for attachment to the end of an adjacent car, a coupling pin having its lower end angular in cross section to conform to said triangular outlined opening, said pin having a shoulder at the inner end of the angular portion and its opposite edge beveled, a rock shaft upon the car and a chain fastened thereto and to said pin at one side of its center of gravity, the beveled portion of the pin adapted to be elevated and rest upon the floor of the recess in which the coupler members are mounted, and a yielding and pivotally mounted coupler head adapted to be mounted upon the end of an adjacent car.

In testimony whereof we hereunto affix our signatures in presence of two witnesses.
